United States Patent Office.

EDWARD RHODES, OF PHILADELPHIA, PENNSYLVANIA, ASSIGNOR TO
HENRY DISSTON & SON, OF SAME PLACE.

Design No. 4,497, dated November 29, 1870.

DESIGN FOR A SAW.

The Schedule referred to in these Letters Patent and making part of the same.

I, EDWARD RHODES, of Philadelphia, county of Philadelphia, State of Pennsylvania, have invented or produced a Design for the Cutting-Edge of a Saw, of which the following is a specification.

The nature of my design is fully represented in the accompanying drawing, to which reference is made.

Claim.

The design for the cutting-edge of a saw, as illustrated in and by the accompanying drawing.

In testimony whereof, I have signed my name to this specification in the presence of two subscribing witnesses.

EDWARD RHODES.
